UNITED STATES PATENT OFFICE.

CHRISTIAN BLUST, OF ST. ALBANS, WEST VIRGINIA.

AUTOMATIC SAFETY CUT-OFF FOR GAS VALVES.

Application filed December 19, 1925. Serial No. 76,491.

This invention relates to certain new and useful improvements in an automatic safety cutoff for gas valves of the type wherein a reduction in gas pressure flowing to an ignited burner or the like is followed by the closing and locking of a valve upon its seat to cut off the supply of gas and to prevent opening movement of the valve upon a subsequent rise of gas pressure.

10 The primary object of the invention is to provide an automatic safety cutoff for gas valves interposed in a gas line between a source of supply and a burner, heater or the like and embodying a spring pressed 15 valve retained in an open position against spring pressure thereon by the flow of gas therethrough and adapted to be seated by said spring when the pressure of the flow of gas becomes lower than the pressure of 20 the spring and having means associated with the valve for locking the same on its seat to prevent opening movement thereof upon a subsequent rise in pressure of the gas.

With the above and other objects in view 25 that will become apparent as the nature of the invention is better understood, the same consists of the novel form, combination and arrangement of parts hereinafter more fully described, shown in the accompanying drawings and claimed.

In the drawing, wherein like reference characters indicate corresponding parts throughout the several views,

Figure 1 is a side elevational view of an 35 automatic safety gas cutoff valve for a heater, burner or the like,

Figure 2 is a cross-sectional view taken 40 on line 2—2 of Fig. 1 showing the circular series of gas entrance openings in the outer end of the valve casing,

Figure 3 is a cross-sectional view taken on line 3—3 of Fig. 1 showing the pin and bayonet slot associated with the valve for retaining the same locked on its seat,

45 Figure 4 is a longitudinal sectional view showing the spring pressed valve closed on its seat under influence of the spring associated therewith, and

Figure 5 is a longitudinal sectional view, 50 similar to Fig. 4 showing the valve unseated in the tension of the spring by gas pressure.

Referring more in detail to the accompanying drawing, wherein is illustrated a preferred embodiment of the invention, the 55 reference numeral 1 designates the valve

casing of tubular formation as shown in Figs. 4 and 5 and having reduced ends 2 and 3, the end 2 being externally threaded as at 4 and internally threaded at 5, while the opposite reduced end 2 is externally threaded at 6 and provided with an end closure wall 7. A gas supply pipe 8 is threaded onto the reduced end 3 of the valve casing, while the coupling 9 attaches the burner supply pipe 10 to the reduced end 2, the coupling 9 being internally threaded as illustrated in Figs. 4 and 5 and enclosing the reduced end 2.

The end wall 7 of the valve casing forms a valve seat, the inner face of said end wall 70 carrying a centrally positioned conical stud or seat 11, the apex 12 of which is disposed axially of the valve casing while said seat 11 is provided with a circular series of longitudinally extending openings 13 disposed 75 adjacent the base of the cone seat 11 as illustrated.

A cylindrical valve 14 having an axial bore 15 therethrough is slidable in the bore 16 of the valve casing 1 and the end thereof 80 adjacent the conical valve seat 11 is formed with a conical recess or cavity 17 coincident to the conical face of the valve seat and to intimately engage the same and overlie the openings 13 for causing passage to the valve 85 as shown in Fig. 4 with the apex 12 of the valve seat received in the bore 15 of the valve 14.

A coil spring 18 within the valve casing 1 engages the inner end of the valve 14 and said spring is placed under tension by the stud screw 19 having the externally threaded shouldered end thereof engaging the internal threads 5 on the reduced end 2 of the valve casing, the adjacent end of the coil spring 18 enclosing the conical extension 20 of the stud screw and engaging said shoulder, the stud screw having a central longitudinal opening 21 extending therethrough. The tension of the spring 18 may 100 be regulated by adjustments of the stud screw 19.

Means associated with the valve casing 1 and valve 14 operate to hold the valve 14 locked upon its seat 11 and includes the provision of a bayonet slot extending through the side wall of the casing 1, the cross slot 22 communicating with the longitudinal slot 23 as shown in Fig. 1 with the side wall of the valve 14 closing the inner 105 110

side of said slot. A pin 24 having a weighted head 25 at its outer end extends through the bayonet slot and has a threaded connection 26 with a side wall of the valve 5 14 as shown in Fig. 3.

When the valve 14 is in its open position as shown in Fig. 5, the pin 24 is disposed in the longitudinal horizontal slot 23 as illustrated by dotted lines in Fig. 1 and with 10 the valve 14 so positioned and removed from its seat 11, the flow of gas received from the supply pipe 8 passes through the openings 13 in the valve seat, the bore 15 of the valve 14, the bore 21 of the stud screw 19 for 15 discharge into the service pipe 10. It is to be assumed that the mean pressure of the gas will be sufficient to overcome the power of the spring 18 for unseating the valve 14, but should the pressure of gas fall while a burner 20 is ignited with a small flame, or the supply of gas through the pipe 8 temporarily cease, the spring 18 will move the valve 14 toward its seat 11 with the conical recess 17 in the outer end of the valve receiving the conical 25 valve seat and closing the passages 13 through the valve seat. When so disposed, the weighted outer end of the pin 24 will cause said pin to move downwardly and be disposed in the transverse or vertical leg 30 22 of the bayonet slot to lock the valve 14 upon its seat so that in the event of a rise of gas pressure in the pipe 8 with a burner associated with the service pipe 10 in an open position, the flow of gas through the 35 valve will be prevented with the valve 14 securely locked upon its seat.

While there is herein shown and described the preferred embodiment of the present invention, it is, nevertheless to be understood 40 that minor changes may be made therein without departing from the spirit and scope of the invention as claimed.

What is claimed is:—

1. In an automatic safety valve for gas 45 burners, a valve casing, an apertured valve seat at one end of the casing, and a tensioned valve having a central opening slid able in the casing, adapted to be held unseated by the flow of gas through the casing and adapted to be spring seated when the flow of gas is reduced to close the seat apertures, said seat being of conical formation with the apertures adjacent the base of the cone and the adjacent end of the valve 50 having a conical socket to receive the seat.

2. In an automatic safety valve for gas 60 burners, a valve casing, an apertured valve seat at one end of the casing, a tensioned valve having a central opening slid able in the casing, adapted to be held unseated by the flow of gas through the casing and adapted to be spring seated when the flow of gas is reduced to close the seat apertures, said seat being of conical formation with the 65 apertures adjacent the base of the cone and

the adjacent end of the valve having a conical socket to receive the seat, and means for locking the valve on its seat.

3. In an automatic safety valve for gas burners, a valve casing, an apertured valve seat at one end of the casing, a tensioned valve having a central opening slid able in the casing, adapted to be held unseated by the flow of gas through the casing and adapted to be spring seated when the flow 75 of gas is reduced to close the seat apertures, said seat being of conical formation with the apertures adjacent the base of the cone and the adjacent end of the valve having a conical socket to receive the seat, and a stud 80 screw adjustably mounted in the other end of the casing engaging the spring to vary tension thereon.

4. In an automatic safety valve for gas 85 burners, a valve casing, an apertured valve seat at one end of the casing, a tensioned valve having a central opening slid able in the casing, adapted to be held unseated by the flow of gas through the casing and adapted to be spring seated when the flow 90 of gas is reduced to close the seat apertures, said seat being of conical formation with the apertures adjacent the base of the cone and the adjacent end of the valve having a conical socket to receive the seat, means 95 for locking the valve on its seat, and a stud screw adjustably mounted in the other end of the casing engaging the spring to vary tension thereon.

5. In an automatic safety valve for gas 100 burners, a valve casing, an apertured valve seat at one end of the casing, a tensioned valve having a central opening slid able in the casing, adapted to be held unseated by the flow of gas through the casing and 105 adapted to be spring seated when the flow of gas is reduced to close the seat apertures, said casing having a bayonet slot in its side wall and a weighted pin extending through the slot and carried by the valve to lock said 110 valve on its seat when moved by the spring to its closed position.

6. In an automatic safety valve for gas 115 burners, a valve casing, an apertured valve seat at one end of the casing, a tensioned valve having a central opening slid able in the casing, adapted to be held unseated by the flow of gas through the casing and adapted to be spring seated when the flow 120 of gas is reduced to close the seat apertures, said seat being of conical formation with the apertures adjacent the base of the cone and the adjacent end of the valve having a conical socket to receive the seat, said casing 125 having a bayonet slot in its side wall and a weighted pin extending through the slot and carried by the valve to lock said valve on its seat when moved by the spring to its closed position.

7. In an automatic safety valve for gas 130

burners, a valve casing having reduced threaded ends, one of said ends being closed, an inwardly directed conical stud on the closed end having a circular series of openings extending therethrough and forming a valve seat, a cylindrical valve having an axial opening and a conical recess in one end to receive the valve seat slidable in the casing, a coil spring in the casing to engage 5 the other end of the valve, an adjustable

stud screw in the casing engaging the other end of the spring to vary the tension thereon, said casing having a bayonet slot in its side wall and a weighted pin extending through the slot and carried by the valve 15 to lock said valve on its seat when moved by the spring to its closed position.

In testimony whereof I affix my signature.

CHRISTIAN BLUST.
